1,006,394. ELECTRIC PUSH-BUTTON.
JACKSON LEE MORRELL, New York, N. Y.
Filed June 9, 1911. Serial No. 632,146.

To all whom it may concern:

Be it known that I, JACKSON L. MORRELL, a citizen of the United States, and a resident of the city of New York, borough of Manhattan, in the county and State of New York, have invented a new and Improved Electric Push-Button, of which the following is a full, clear, and exact description.

Among the principal objects which the present invention has in view are: to provide a resilient rest for the plug employed in buttons of the character named which forms an even support therefor to avoid the rocking of the button when depressed to complete the electric circuit in which it is incorporated; to provide contacting members for completing the circuit arranged to avoid the usual carbonizing thereof; to extend the supporting base of the resilient member of the button; and to reduce the labor of assembling the button.

One embodiment of the present invention is disclosed in the structure illustrated in the accompanying drawings, in which like characters of reference denote corresponding parts in all the views, and in which—

Figure 1 is a face view of a button constructed and arranged in accordance with the present invention; Fig. 2 is a vertical cross section of a button constructed in accordance with the present invention, the section being taken on the line 2—2 in Fig. 3; Fig. 3 is a vertical cross section taken on the line 3—3 in Fig. 2; and Fig. 4 is a detail view of the base plate and contacting mountings thereon, the cap and plug being removed.

As shown in the accompanying drawings, the base plate 9 is constructed from any suitable insulating material, such as rubber or fiber. The plate 9 is secured to the standing structure by any suitable means. The means are not herein indicated as they would vary according to the nature of the structure. The preferred form of securing the cap 10 to the base plate 9 is that shown in Figs. 2 and 3 where the plate 9 is depicted as having a screw thread formed on its periphery. A registering internal thread is formed on the cap 10 whereby the same is screwed into holding position upon the plate 9 when the plate is secured to the standing structure. As in usual constructions the cap 10 is provided with a recessed portion 11 having a central perforation formed therein for the extension therethrough of the plug 12. The plug 12 is of ordinary construction, having a base flange to prevent the projection of the plug through the perforation in the cap 10. The plug 12, in the present invention, rests upon the flat top sections 13, 13, equally disposed and laterally extended from the pendant wedge section 14. The

section 14 is drawn to as close an angular edge at the lower end thereof as the nature of the material permits. The metal forming the spring seat for the button, and incorporated in the sections 13 and 14, is slightly restricted adjacent the sections 13 to form the two bent sections 15, 15 each removed an equal distance from the wedge section 14 and each connected with one of

the foot plates 16. The foot plates 16 are shaped and extended substantially as shown in Fig. 4 of the drawings. The extensors of the two plates 16 are upon opposite sides of the sections 13 and 15, thus forming supporting members for the spring rest for the plug 12, the rocking tendency whereof is largely diminished.

To minimize the labor for assembling the plate 9 and spring rest for the plug 12, each of the foot plates 16 is provided with a spur extension 17 which is sharpened and pressed into the plate 9. The opposite ends of the plates 16 are perforated to pass the shank of the screws 18 and 19. The screw 19 is utilized as a binding screw for the terminal 20 of the electric circuit.

Connected to the opposite branch of the electric circuit is a contact plate 21. The plate 21 is upturned at one end to form a ridge 22. As seen in Fig. 2 of the drawings the ridge 22 is disposed beneath and perpendicular to the wedge section 14. The plate 21 is secured to the base plate 9 by means of a screw 23 which is also utilized as a binding screw for connecting the terminal 24 of the opposite branch of the electric circuit.

When the button is completed and assembled, as shown in the drawings, it will be found that the spring seat of the plug is of an even and non-rocking character. The bent sections 15 provide for an even resistance of both sides of the spring seat of the bearing edges of the button. It will also be found that the oppositely disposed foot plates 16, 16 overcome any tendency to rock on the median line of the spring seat; and further, that the cost of assemblage, so important in articles of this kind, is materially reduced over the cost for the same class of work in the present ordinary construction. By the arrangement wherein the ridge 22 and the contracted edge of the wedge section 14 are crossed, a crossed knife-like junction is formed which tends to break down any accumulation of carbon formed on the edges of each of the members due to the slight arc when breaking the current.

Having thus described my invention, what I claim as new and desire to secure by Letters Patent is:—

1. An electric push button having a removable cap, a base plate and a reciprocating plug, an elongated seating spring having at both ends thereof bended spring sections and in the center thereof a pendant wedge section; and a contacting member mounted

1006394

on said base plate having an upturned contacting ridge formed thereon, said ridge being disposed perpendicular to the extension of the said wedge section formed on said spring.

2. An electric push button having a removable cap, a base plate and a reciprocating plug, an elongated seating spring for said plug bended at the center thereof to form a pendant wedge shaped section and provided at both ends thereof with oppositely extended foot plates, each of said foot plates being provided at one end thereof with spurs for insertion in said base plate and at the other end thereof with a perforation to receive structural fastening devices; and a contact plate having formed at one end thereof an upturned ridge-like edge and at the other end thereof a perforation to receive a structural fastening member, said ridge-like edge being disposed perpendicular to the edge of said wedge shaped section, the said contact plate and said spring each being incorporated in the electric circuit.

In testimony whereof I have signed my name to this specification in the presence of two subscribing witnesses.

JACKSON LEE MORRELL.
